10 Claims

ABSTRACT OF THE DISCLOSURE

A harpsichord wherein each plucking means thereof is comprised of a jack controlled by an associated key and a plectrum carrying tongue pivotally mounted to the vertically upper end of the jack. The pivotal mounting of the tongue is such as to cause the plectrum to arc away from its associated string after plucking it so that as the jack drops vertically following the plucking action the plectrum will not restrike the string. Means are present to reposition the tongue for plucking action by the plectrum.

The present invention relates to string musical instruments wherein the strings are played by a plucking action. The harpsichord is the best known instrument of this type.

In a harpsichord and similar instruments, it is conventional to have the plucking action of the strings controlled by keys very similar to those in a piano. The keys are pivotally mounted to the frame of the harpsichord and each key controls an individual jack associated therewith for plucking the string of the instrument in order to produce the desired sound. The jacks are movable vertically by the key action and each jack has a little plucking finger, known as a plectrum, provided on the vertically upper end thereof, which plectrum plucks the string as the jack is raised vertically by its controlling key.

Heretofore it has been very difficult to insure that proper plucking action of the string can continuously be achieved due to the fact that there is appreciable lateral shifting of the strings due to temperature or humidity changes. Also, movement of a series of jacks laterally to take a register out of play may result in improper repositioning of one or more jacks. As a result, the strings may be closer or farther away from the individual plectra that are to pluck them than is desirable so that the plectra either pluck too strongly, too weakly, or not at all. Also, the plectrum sometimes catches on the strings with a jack remaining suspended and inoperative until corrected by manual adjustment. Usually the plectrum strikes the string a second time as the jack drops back into position after being vertically raised by the key to achieve a first plucking action. Such a second striking causes appreciable undesirable sound which interferes with the overall musical sound quality of the instrument.

It is the general object of the present invention to overcome the above-mentioned difficulties in the prior art by providing a plectrum carrying tongue which is pivotally mounted to the vertically upper end of the jack. The pivotal mounting of the tongue causes the plectrum to pivotally retract away from the string after a plucking action. Means are provided to hold the plectrum in its retracted position after the plucking action so that the plectrum will easily clear the string as the jack drops following the plucking action. Spring means associated with the tongue are provided to return the tongue to its proper position for the next plucking action.

Another object of the present invention is to provide a buffer means associated with the plectrum, which buffer

2

means is adapted to be brought into engagement with the string after the jack has fallen to its lowest position whereby the string, jack and plectrum are positioned in desirable operative relation.

For a better understanding of the apparatus of the invention, reference should be had to the accompanying drawings wherein:

FIGURE 1 is a fragmentary side elevational view, partially shown in vertical section, of a key and plucking means associated therewith for a string musical instrument, such as a harpsichord, the means shown comprising a preferred embodiment of the invention;

FIGURE 2 is a fragmentary end elevation of the embodiment illustrated in FIGURE 1;

FIGURES 3 and 4 are both fragmentary side elevational views, partially shown in vertical section, of the embodiment of the invention utilized to achieve the self-sustaining feature of the harpsichord;

FIGURE 5 is a side elevation of a plectrum carrying tongue which can be utilized in the improved harpsichord of the invention wherein the plectrum and buffer are an integral unit; and

FIGURES 6 and 7, respectively, are a side and end elevation, of another variation of a plectrum carrying tongue wherein the buffer associated with the plectrum is adjustable.

Now referring to the drawings in greater detail, and with particular reference to FIGURES 1 and 2, a stringed musical instrument of the plucking type, such as a harpsichord, is indicated as a whole by the numeral 10. For purposes of clarity, only one key 12 and its associated members is shown, but it should be understood that several keys are provided in the harpsichord and that the principles of the invention shown are readily applicable to any and all of such keys on one or more keyboards, as desired.

The key 12 is pivotally balanced on a balance rail 16 which rests on and is secured to the key bed (not shown). A felt washer 14 is positioned between the balance rail 16 and the key 12 to cushion the key and to allow noiseless pivotal movement thereof. The key 12 receives a positioning pin 18 extending from the balance rail and engaging a slot in the key for pivotally mounting the key 12 to the frame 14. The key 12 is played by depressing the front or exposed end thereof in a conventional manner. The harpsichord includes any suitable number of playing strings 20 positioned in a conventional manner on supports provided in the frame 16. The strings 20 are usually horizontally positioned and are relatively closely spaced from each other in a horizontal plane. The string 20 usually is made from wire and is adapted to be plucked by use of a jack 22. The jack 22 is substantially rectangular in shape and is adapted to be raised in order to achieve plucking of the string 20 by depressing the front end of the key 12. In order to achieve the actual plucking of the string 20 as the jack 22 is vertically raised, a tongue 24 is pivotally mounted to the bifurcated upper end of the jack 22. A pin 26 is received by the bifurcated legs of the jack 22 and such pin 26 forms the pivotal mounting for the tongue 24. A plectrum 28 is mounted to and extends from the tongue 24 and it is the plectrum 28 which achieves the plucking action of the string 20 as the jack 22 is vertically raised by its controlling key 12.

The jack 22 has a jack rail 30 positioned thereabove, and a suitable layer of cushioning material 32 is provided on the under surface of the jack rail above the bifurcated end of the jack 22 in order to limit or control vertical upward movement on the jack. A pair of jack guides 34 and 36 are provided also to position the jack and such jack guides are slotted in order to receive the jack 22 and

position it for controlled vertical upward or downward movement only.

It is a particular feature of the present invention to provide a leaf or wire spring 38 associated with the tongue 24, which spring normally urges the tongue 24 to a substantially vertically upright position, as is illustrated by FIGURE 2. One end of the spring 38 is suitably connected to the tongue 24 and the free lower end of the spring usually is curved upwardly and laterally offset from the tongue to bias against the jack guide 34 when the jack 22 is in its lowest position in order to move the pivotally mounted tongue 24 to a vertically upright position. When the tongue 24 is substantially vertically upright, the plectrum 28 is in proper position to pluck the string 20 as the jack 22 is raised.

As a result of the spring 38 properly positioning the tongue 24, as the key 12 is depressed to raise the jack 22 vertically, the plectrum 28 plucks the string 20. As the jack 22 is vertically raised, however, the free end of the spring 38 raises off of the jack guide 34 to relieve the spring pressure directed against the tongue 24. Accordingly, as the plectrum strikes the string 20, the tongue 24 is free to pivot away from the string 20 following the plucking action. This occurs since the force of the plectrum plucking the string creates an equal and opposite force causing the plectrum to pivotally retract from the string after it plucks the string.

In order to keep the plectrum 28 pivotally retracted away from the string 20 so that it will clear the string 20 as the jack 22 drops back into its lowest position, an adjusting screw 40, threadably received in the lower end of the tongue 24 is provided. The adjusting screw 40 is adapted to engage with a bushing 42 which is received in the tongue and surrounds the pivot pin 26. Such bushing usually is made from a soft deformable material such as felt. The combination of the adjusting screw 40 and the bushing 42 allows the adjusting screw to be rotated inwardly to selectively compress the bushing 42 about the pivot pin 26 in order to control the pivotal action of the tongue 24. Use of the bushing 42 causes the tongue 24 to remain in a retracted or slightly slanted position after the plucking of the string 20 so that as the jack 22 drops, the plectrum 28 drops past the string 20 without restriking it thereby eliminating the undesirable sound mentioned hereinbefore.

As the plectrum 28 drops past the string 20, the free end of the spring 38 reengages the jack guide 34 to bias the tongue 24 back into a vertically upright position. As a further feature of the invention, a buffer member 44 is mounted on the plectrum 28 and extends upwardly therefrom but leaves a predetermined length of the plucking tip of the plectrum exposed. The buffer may be made from any suitable material such as buckskin, sponge, foam rubber, or plastic. As the spring 38 biases the tongue forwardly, the buffer is moved towards the string until the string is at the forward connection of the buffer to the plectrum and the string and plectrum are in ideal plucking relation. It becomes apparent with the type of plectrum positioning action described that lateral shifting of the string 20 will not cause the plectrum 24 to engage or pluck the string 20 too strongly or weakly on any subsequent plucking action because use of the spring 38 and the buffer 44 insures the same amount of plectrum engagement of the string at all times. The buffer 44 can be mounted on the plectrum 28 in any suitable manner as by cement or adhesive. Such member could, for example, be made from a plastic substance.

FIGURES 3 and 4 refer to a slight variation of the embodiment illustrated in FIGURES 1 and 2 wherein a self-sustaining feature is added to the harpsichord of the invention. In this modification, as the front of the key 12a is depressed, the rear portion of the key is raised in like manner to the key 12 of FIGURES 1 and 2. Mounted to the rear portion of the key 12a is an upwardly and rearwardly extending leaf spring 50 which is secured at one

end to the key 12a and is operably associated with a vertically movable control rod or rod member 52 slidably received by suitable receiving slots provided in the jack guides 34a and 36a. The vertically lower end of the control rod 52 is adapted to be engaged by the leaf spring 50 whereby depressing the key 12a causes the leaf spring 50 to vertically raise control rod 52.

The other or upper end of the control rod 52 is adapted to operatively engage with a suitable spring 38a, usually a wire, whereby, as in FIGURES 1 and 2, a pivotally mounted tongue member 24a is brought to a substantially vertically upright position as the control rod 52 is raised.

Due to the fact that the clearance between the leaf spring 50 and the lower end of the control rod 52 is substantially less in distance than the clearance between the key 12a and jack 22a, depressing the key 12a at the front end thereof causes the control rod 52 to be vertically raised before the rear of the key lever 12a will strike the jack 22a to cause the jack 22a to also be vertically raised.

As a result, when the key 12a is depressed or played, the control rod 52 is raised to effect movement of the tongue 24a and its plectrum 28a to an operative position before any vertical upward movement of the jack 22a is effected. A buffer 44a on the plectrum 28a insures proper plucking action on the string 20a, as the jack 22a is vertically raised.

The plucking action of the string 20a by the plectrum 28a causes the tongue 24a to swing or pivot away from the string 20a and such pivotal action of the tongue 24a is not impeded because an adjustable sleeve member 54 is provided on the control rod 52, which sleeve member 54 strikes the jack guide 36a to limit the vertical upward movement of the control rod 52. An adjusting screw 40a and a bushing 42a similar to the adjusting screw 40 and bushing 42 of FIGURES 1 and 2 are associated with the tongue 24a in order to keep the tongue in a retracted or slanted position after such tongue pivots away from the string 20a following the plucking action.

As the jack 22a is allowed to drop following the plucking action of the string 20a, the tongue 24a also drops but since the plectrum 20a is held in a pivotally retracted position, it will clear the string 20a on its downward drop without restriking it. Additionally, even as the jack 22a falls to its lowest position, the free end of the leaf spring 38a still does not contact the upper end of the control rod 52 and the sound produced by the vibrating string 20a will be sustained. In order to dampen such sustaining sound of the string 20a, any conventional dampening means and controls are provided in the instrument.

An adjustable sleeve 56 is suitably carried on the jack 22a in order to limit the downward movement of the jack 22a after the plucking action to insure that proper clearance will remain between the key 12a and the lower end of the jack 22a.

FIGURE 5 illustrates a slight modification of the tongue, plectrum and buffer combination which can be utilized in the harpsichord of the invention wherein the plectrum and buffer are formed from a one-piece member 60.

FIGURES 6 and 7 illustrate another modification wherein the buffer 44b is adjustably mounted to the tongue 24b, as by screws 62 which secure the top end of the buffer 44b to the tongue 24b. The buffer 44b may be made from a thin spring metal sheet. A second adjusting screw 64 threadably received in the tongue 24b is provided, which screw can be selectively rotated to control the position of the free or bottom end of the buffer whereby the buffer can be properly positioned in relation to the string 20b. In this embodiment, the plectrum 28b extends

through a slot 66 in the face of the buffer 44b in order to be in proper position to pluck the string 20b as the tongue 24b is raised by its associated jack. The tongue 24b has its position controlled as in the other embodiments of the invention.

It is seen from the foregoing that the tongues are urged

forwardly towards an associated wire before the jack carrying the tongue is actuated for string plucking action. The buffers carried by or associated with the plectrum hence engage the associated string and insure ideal plucking relationship therebetween so that novel means and controls are present to compensate automatically for any out of position relationship between a string and its plectrum.

While a certain representative embodiment and details have been shown for the purpose of illustrating the invention, it will be apparent to those skilled in this art various changes and modifications may be made therein without departing from the spirit or scope of the invention.

What is claimed is:

1. In a musical instrument having a frame, a plurality of strings secured to the frame, a plurality of pivotally positioned keys, and a plurality of plucking means individually operably associated with the individual strings and controlled by the keys, each plucking means including a vertically movable jack, the jacks being aligned and defining a vertical plane, the improvement comprising

a tongue member pivotally mounted to the vertically upper end of each jack,

a plectrum mounted on said tongue member and adapted to pluck the string associated therewith as the jack is moved vertically upwardly by its controlling key, said tongue pivotally retracting to a slanted position away from the string after the plucking action, and

means operably associated with said tongue and including a spring having its upper end attached to said tongue and having a dependent free lower end which can be engaged by a member for urging said tongue back to a substantially vertically upright position after the jack drops after the plucking action.

2. The combination according to claim 1 and including means holding said plectrum in a slanted position to clear the string as the jack drops vertically downwardly after the plucking action.

3. The combination according to claim 1 and including buffer means operatively associated with said plectrum adapted to be brought into engagement with the string when said means associated with said tongue return the tongue to a substantially vertically upright position.

4. The combination according to claim 1 wherein said spring has its lower end normally biased against a frame portion to urge the tongue into an upright position but wherein vertical upward movement of the jack moves the free end of the spring out of engagement with said frame portion to allow free pivotal movement of the tongue.

5. The combination according to claim 1 wherein the vertically upper end of the jack has a bifurcated end, the legs of the bifurcation receiving a pin forming the pivotal mounting of the tongue.

6. The combination according to claim 5 wherein the means holding said plectrum in a slanted position after the plectrum pivotally retracts away from the string following the plucking action include

bushing means received by said tongue and surrounding said pin, and

adjustable screw means threadably received by said tongue and engageable with said bushing whereby rotation of said adjusting screw means effects selective compression of said bushing means about said pin to control the pivotal action of said tongue.

7. The combination according to claim 1 wherein said means urging said tongue back to a vertically upright position include,

a spring mounted to each key,

a vertically movable control rod associated with each jack, the vertically lower end of each control rod

being adapted to be engaged by a respective key spring whereby depressing the front end of the associated pivotally positioned key effects vertical upward movement of the rod, and

said first-named spring having its free lower end adapted to be engaged by the vertically upper end of the control rod as it is moved vertically upwardly whereby as the key spring engages the control rod the tongue is biased forwardly by said second spring into a substantially vertically upright position.

8. The combination according to claim 7 wherein the clearance between the key spring and the lower end of the control rod is less than the clearance between the key and its associated jack whereby depressing the front end of the key causes the control rod to be raised to move the tongue into a vertically upright position before the jack is raised vertically to effect a plucking action.

9. The combination according to claim 3 wherein said buffer means is made from a suitable compressible material adapted to dampen the associated string as it is brought into contact therewith, the material mounted on the plectrum and extending upwardly therefrom, but leaving a predetermined length of the plucking tip of the plectrum exposed whereby as the buffer is moved into contact with the string, the string and the plectrum are in ideal plucking relation.

10. In a musical instrument having a frame, a plurality of strings secured to the frame, a plurality of pivotally positioned keys, and a plurality of plucking means individually operably associated with the individual strings and controlled by the keys, each plucking means including a vertically movable jack, the jacks being aligned and defining a vertical plane, the improvement comprising

a tongue member pivotally mounted to the vertically upper end of each jack,

a plectrum mounted on said tongue member and adapted to pluck the string associated therewith as the jack is moved vertically upwardly by its controlling key, said tongue pivotally retracting to a slanted position away from the string after the plucking action, and

means operably associated with said tongue for urging said tongue back to a substantially vertically upright position after the jack drops after the plucking action, said means including

a leaf spring mounted to each key, a vertically movable control rod associated with each jack, the vertically lower end of each control rod being adapted to be engaged by a respective key spring whereby depressing the front end of the associated pivotally positioned key effects vertical upward movement of the rod, and

a second leaf spring having an end connected to the tongue and a free end adapted to be engaged by the vertically upper end of the control rod as it is moved vertically upwardly whereby as the leaf spring engages the control rod the tongue is biased by said spring into a substantially vertically upright position.
